SPOON OR SIMILAR ARTICLE

Charles O. Bliss, P.O. Box 47607, Los Angeles, Calif.

Filed May 11, 1965, Ser. No. 85,219

Term of patent 14 years

(Cl. D44—29)

FIG. 1 is a top perspective view of a spoon or similar article, showing my new design;

FIG. 2 is a top plan view thereof;

FIG. 3 is a side edge view thereof; and

FIG. 4 is a sectional view on the line 4—4 of FIG. 1.
I claim:

The ornamental design for a spoon or similar article, substantially as shown.
